UNITED STATES PATENT OFFICE.

ELLWOOD M. SHANNON, OF BALA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

THROTTLE VALVE.

Application filed July 5, 1924. Serial No. 724,463.

My invention relates to improvements in throttle valves having two seats.

One object of the invention is to construct the valve so that it will close against both seats at all times.

A further object of the invention is to construct the valve so that one portion will yield to allow both parts thereof to seat themselves properly.

10 A still further object of the invention is to locate the valve in the smoke box of a locomotive between the superheater head and the pipes leading to the cylinder.

15 In the accompanying drawings: Fig. 1 is a sectional view on the line 1—1, Fig. 2, illustrating my improved throttle valve;

20 Fig. 2 is a side view illustrating the location of the throttle valve in the smoke box of a locomotive; and

25 Fig. 3 is a sectional plan view on the line 3—3, Fig. 1, illustrating the passages in the valve.

Referring to the drawings, 1 is the shell 25 of the boiler. 2 is the front tube sheet to which are attached the flue tubes. 3 is the smoke stack. 4 is a deflecting plate, directly back of the smoke stack, which is used when oil is the fuel. The head 5 of the superheater is located in the smoke box 6 of the boiler in front of the tube sheet 2 and has circulating tubes 7, which extend into the flue tubes in the ordinary manner. Mounted on the portion 8 of the superheater is a casing 9, 30 which encloses the throttle valve 10. A rock shaft 11 is actuated in any suitable manner from the cab of the locomotive and has an arm 12 connected by a link 13 to the throttle valve 10.

40 In the present instance, the link 13 is connected to a small valve 14, which has a limited movement to allow steam to enter tangential channels 15 in the body of the valve 10 to permit a certain amount of steam to enter 45 the cylinders while the locomotive is drifting. These passages are formed in the tangential ribs of the valve 10, as shown clearly in Fig. 3. In some cases, this valve may be omitted, in which instance the link 13 is 50 connected directly to the valve 10. The tangential ribs connect the spaced inner and outer portions of the valve as shown in Fig. 3, and prevent distortion from unequal expansion and contraction. The valve 10 has

a lower seating flange 16, which rests on a 55 seat 17 in the valve casing. Below this seating flange is a guide portion 18, which slides within the extension 19 of the casing. At the upper end of the valve is a seating ring 20, which is shaped to rest upon a seat 21, in 60 the valve casing 9. Directly below this ring is a guide ring 22, which is cast integral with the valve 10 and is adapted to slide in the portion 23 of the casing below the seat 21. The ring slides on the upper portion 24 65 of the valve. In this portion is a ring 25, which has a working fit against the ring 20. The ring 20 is connected to a hub 26 by ribs 27. Located in a recess in the hub is a spiral spring 28, which is seated in the bottom of a 70 recess and against a nut 29 that is screwed onto the threaded portion 30 of a projection of the valve. The ring 20 is so proportioned in regard to the seating flange 16 that, when the valve is closed, the ring 20 75 will seat itself, first on its seat 21 and then the spring will yield to allow the seating flange 16 to come in contact with the seat 17, thereby making a tight joint at the upper and lower portions of the valve. This construction insures a tight fit of the valve on both seats of the casing under all conditions. 80

While my invention is shown as adapted to be located in the smoke box of a locomotive, and, preferably on the superheater head, 85 it will be understood that it can be located in the steam dome of the boiler, or other convenient place, without departing from the essential features of the invention.

I claim:

1. The combination of a valve casing having two seats; a throttle valve located in the casing and having a seating flange for one of said seats; a centrally located portion projecting from the valve and threaded at 95 its end; a recessed slidable hub mounted on the said portion; a spring located within the recess; a nut on the threaded portion against which the spring bears; arms projecting from the hub; and a seating ring 100 carried by the arms and arranged to close yieldingly against the other seat of the casing.

2. The combination of a valve casing having two seats; a valve mounted in the casing and having a seating flange and a yieldingly seated ring for the respective seats; a series of tangential passages in the valve 105

between the seating portions; a small valve controlling the flow of steam through these passages; and an operating link connected to the valve so that the small valve will be operated in advance of the main valve.

3. The combination of a valve casing having two seats; a valve mounted in the

casing and having spaced inner and outer portions and having a seating flange and a yieldingly seated ring for the respective seats; and tangential ribs connecting said inner and outer portions of the valve.

ELLWOOD M. SHANNON.
